Patented July 5, 1966

205,183

FISHING TOOL FOR MULTIPLE USES

John C. Micklitsch, 112 S. Johnson St., Bluffton, Ind.

Filed Aug. 2, 1965, Ser. No. 86,401

Term of patent 14 years

(Cl. D31—4)

FIG. 1

FIG. 2

FIG. 3

FIGURE 1 is a perspective view of one side of the fishing tool showing the tool in an unlocked position;

FIGURE 2 is a top view of the fishing tool illustrated in FIGURE 1; and,

FIGURE 3 is a perspective view of the other side of the fishing tool illustrated in FIGURE 1.

I claim:

The ornamental design for a fishing tool for multiple uses, as substantially shown and described.
